UNITED STATES PATENT OFFICE.

THOMAS R. BROWN, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

CAR AND TRAIN-PIPE COUPLING.

1,386,235.

Specification of Letters Patent.

Patented Aug. 2, 1921.

Original application filed March 6, 1917, Serial No. 152,695. Divided and this application filed July 5, 1919. Serial No. 308,874.

To all whom it may concern:

Be it known that I, THOMAS R. BROWN, of Pittsburgh, in the county of Allegheny and State of Pennsylvania, have invented 5 a certain new and useful Improvement in Car and Train-Pipe Couplings, of which improvement the following is a specification.

This invention relates to combined car 10 and train pipe couplings, and has for its object to provide improved valve means for controlling the train pipe passages.

This application is a division of my original application Serial No. 152,695, filed 15 March 6, 1917.

The figure of the accompanying drawing is a diagrammatic sectional view, showing counterpart couplers coupled together, and embodying my improvement.

According to the construction shown, my 20 improvement is applied in connection with a coupler of the rigid lock type, that is, one in which the counterpart couplers are each provided with projecting portions having 25 vertical plane surfaces arranged in an inclined or diagonal direction, whereby the couplers engage each other with a relative longitudinal and lateral movement during the coupling action, and each coupler also 30 having a pivoted lock or cam lever adapted to be automatically clamped against a corresponding surface on the counterpart coupler.

These locking levers, 6, are normally 35 pressed outward by the springs, 7, acting on the pistons, 8, mounted in cylinders, 9, and connected by rods, 10, with the pivoted locks for releasing the same with fluid pressure admitted to said cylinders. The body 40 portion, 11, of the coupler contains the passages for the fluid pressure conduits, such as the reservoir line connection, 12, and the train brake pipe passage, 13, said passages being formed in a diagonal direction in line 45 with the approach movement of the coupler heads and provided with suitable gaskets at the meeting face of the coupler located at right angles to said passages. In the main reservoir passage are placed the valves, 50 14, having stems, 15, extending out through the gasket openings and adapted to engage each other and thereby open the valves in the two couplers when the same are brought

together. The train brake pipe passages are controlled by the piston valves, 16, having 55 springs, 17, for normally closing said valves against their seats, the pressure in the chamber back of each piston valve being governed by a small valve, 18, having a stem, 18^a, actuated by a piston, 19, in chamber, 60 20, for controlling the port, 21, communicating with a pipe, 22, which may be connected with a manually operated valve 50. A supply port, 23, leads from the main reservoir passage to the piston chamber, 20. 65

The operation of my improved device is as follows: When the couplers are brought together in the act of coupling, the stems, 15, of the valves, 14, in the main reservoir line passage engage each other and cause 70 an unseating of the valves, 14, and permits the air from main reservoir pipe to flow through the coupling and equalize on the two cars. At the same time air flows through the port, 23, into the chamber, 20, 75 forcing the piston, 19, against the stem, 18^a, to unseat the small vent valve, 18, thereby releasing air under pressure from the back of the piston valve, 16, in the brake pipe passage, 13, and causing said brake pipe 80 valve to open by the pressure from the brake pipe passage acting upon its opposite face. This valve is thus forced back against its spring, 17, until it seats against a gasket ring, as indicated, thereby preventing leakage around the valve, and holding the same 85 in the full open position. The space back of pistons, 16 and 19, is then in communication with the atmosphere through the port, 21, pipe, 22, and exhaust ports of the usual 90 controlling valve, 50.

When it is desired to uncouple the cars, air under pressure is admitted by the valve, 50, from supply pipe, 52, to the passage, or pipe, 22, from which it flows into the unlocking cylinder, 9, and through passage, 21, into the chamber back of piston, 16, thereby equalizing the pressure thereon so that the spring, 17, forces the valve to its seat and closes the brake pipe passage. At the same 100 time the air passing into cylinder, 9, forces the piston, 8, outward and releases the coupler lock, 6. The couplers may then be pulled apart, and when this is done the main reservoir line valves automatically 105 close, and air escapes from chamber, 20,

through passage, 23, to the atmosphere. The vent valve, 18, is then closed and held closed by the pressure of air from the train pipe passage, 13, which equalizes around the 5 piston, 16, into the chamber back of said piston.

It will, of course, be understood that in the actual construction, the reservoir line passage and the brake pipe passage at the 10 face of the coupler are located one above the other.

In the event of an accidental parting of the couplers, the valve, 16, in the brake pipe, will not close immediately, as there is only atmospheric pressure back of the valve, and it will remain in its open position until the brake pipe pressure, acting on the face of the valve, has diminished below the force of the spring, 17. This reduction in brake 20 pipe pressure, during this period of time, will be sufficient to cause a full application of the automatic brakes.

Having now described my invention, what I claim as new and desire to secure by Letters Patent is:

1. In a coupler having passages for automatically connecting the train pipe lines, a closing piston valve for the brake pipe passage, a small valve for venting fluid from 30 the chamber behind said piston, another piston for actuating said vent valve, and a tappet valve operated by the coming to-

gether of the counterpart couplers for supplying fluid to said actuating piston.

2. In a coupler having passages for automatically connecting the train pipe lines, a closing piston valve for the brake pipe passage, a small valve for venting fluid from the chamber behind said piston, another piston for actuating said vent valve, and a tappet valve located in the main reservoir passage for controlling a supply of fluid to said actuating piston.

3. In a coupler having passages for automatically connecting the train pipe lines, a closing piston valve for the brake pipe passage, a small valve for venting fluid from the chamber behind said piston, and a manually operated valve for controlling a supply of fluid through the vent valve into the 50 chamber behind said piston valve.

4. In a coupler having passages for automatically connecting the train pipe lines, a closing piston valve for the brake pipe passage, a small valve for venting fluid from 55 the chamber behind said piston, another piston for actuating said vent valve, means for supplying fluid to said actuating piston, and a manually operated valve for controlling a supply of fluid through the vent valve 60 into the chamber behind said piston valve.

In testimony whereof I have hereunto set my hand.

THOMAS R. BROWN.
